UNITED STATES PATENT OFFICE.

ANTHONY J. GRIFFIN, OF NEW YORK, N. Y.

GUIDING DEVICE FOR TROLLEYS.

SPECIFICATION forming part of Letters Patent No. 678,617, dated July 16, 1901.

Application filed November 6, 1900. Serial No. 35,649. (No model.)

To all whom it may concern:

Be it known that I, ANTHONY J. GRIFFIN, a citizen of the United States, residing in the borough of Manhattan, in the city and county 5 of New York, State of New York, have invented certain new and useful Improvements in Guiding Devices for Trolleys, of which the following is a specification.

This invention relates to devices for guiding trolleys upon and for preventing their escape from the line or circuit-wire of the system.

Primarily the object of my invention is the provision of guiding arms or levers having outwardly-flaring ends, said levers being mounted for free and independent swinging movement upon the bolt or axle carried by the fork of the trolley-pole or other support and upon which the trolley or contact wheel 20 is mounted for rotation.

A further object of the invention is the provision of guides consisting of arms or levers having flaring or outwardly-curved ends, said arms or levers being loosely journaled 25 upon the axis of the trolley and having weighted ends, by which means they are always caused when not in contact with a switch or other obstruction to assume vertical positions with relation to the circuit-wire.

A further object of the invention is the provision, in connection with a trolley-pole or other suitable carrier, of arms or levers independently journaled on the trolley-axle 35 at each side thereof and each having an outwardly-curved and tapered end for guiding the pole in such a manner that the trolley will always be caused to seek the wire and also having weighted lower ends by which, no 40 matter what may be the position of the pole, the guiding attachments will be caused automatically to assume vertical positions.

A further object of the invention is the provision of guides of improved construction 45 journaled upon the axle on which the trolley is loosely mounted and provided with overhanging lips or guards curved to conform to the circumference of the trolley-wheel, thereby preventing the entrance of the circuit-wire between said wheel and the sides of the guards.

A further object of the invention is the

provision of guiding arms or levers so formed that they will not interfere with the crossing-plates or switches when the arms are passing 55 under the same.

In the accompanying drawings, Figure 1 represents a side elevation of my invention. Fig. 2 is a plan view thereof, showing the guiding attachments in their normal vertical 60 positions. Fig. 3 is a plan view showing said attachments as swung or tilted to a horizontal position by contact with a switch, crossing, or other obstruction; and Fig. 4 is a sectional view of one of the guiding arms or levers, taken on line 11, Fig. 1.

Similar characters designate like parts throughout the several views.

Referring to the drawings, the numeral 10 designates a trolley-pole (or it may be any 70 other suitable carrier) of common construction, having a bifurcated end 10', the usual cross bolt or bar 12, and a trolley or contact wheel 13 loosely mounted between the arms of the fork upon said bolt 12. Loosely journaled for free and independent swinging movement upon the bolt 12 and at each side of the bifurcated portion 10' of the trolley-pole are guiding arms or levers 14, each of which is provided with a hub 14', sleeved 80 upon the bolt 12, with a guiding end 15, outwardly curved at 15', on its inner side, said end terminating in a point 15² and with a weighted extremity 16, which is curved at its inner side at 16' to conform to the exterior 85 contour of the bifurcated portion 10' of the pole. Formed on each of these arms or levers 14 and concentric with the axis thereof is a guiding lip or flange 17, conforming to the periphery of the flange of the trolley and 90 serving to prevent the line or circuit wire 18, with which the trolley is in engagement, from becoming wedged between the sides of the trolley and the bifurcated portion of the trolley-pole.

As will be seen by reference to Fig. 1, the weighted arms or levers 14 tend normally to assume a vertical position; but when the trolley 13 is passing under a switch, "crossing," or other obstruction the curved outer 100 edges of said arms 14 will, by contact with the obstruction, cause the arms to be depressed to the position shown by dotted lines in Fig 1, and after passing said obstruction

the arms will by gravity immediately assume the vertical position shown in full lines in said figure.

To afford clearance while the trolley is passing under a switch or crossing, the guiding end 15 of each lever or arm 14 is curved or concaved, as at 15³, on its outer side, so that said side will not come into contact with the guiding-ribs of the switch or crossing-plate 10 as the contact-wheel passes thereunder. In virtue of this construction it will be seen that when the arms or levers 14 are brought to a horizontal position by contact with a switch or crossing-plate and their outer ends are 15 depressed, as illustrated in Fig. 3, the guiding-ribs on said plate will pass in a straight line over the concaved portions 15³ of the arms without interference therewith.

In the use of my invention when it is desired to place the trolley upon a circuit-wire the flaring ends 15' of the levers 14, which curve outward for some distance on each side, will guide the trolley to its seat upon the wire, and after leaving a switch or other obstruction under which the trolley passes these arms will automatically assume vertical positions and will prevent the trolley from jumping off the wire—as, for instance, when rounding curves of short radius—the 25 weighted ends 16 always causing said arms or levers to assume, when free from contact with extraneous obstructions, vertical positions on each side of said wire.

My invention is not limited to the exact devices shown and described, for changes may be made without departure therefrom.

The arms or levers 14 constitute a means of maintaining the trolley-wheel free of ice in winter, since the overlapping shoulders or 40 flanges 17 and the edges 17' ride close to the circumference and sides of such wheel and act as scrapers to clear the same from ice and snow.

Having thus described my invention, what 45 I claim is—

1. The combination, with a support, of a contact-wheel, and independently-mounted movable guides extending outwardly beyond the sides of said wheel, each of said guides 50 having a recess or concavity adjacent to its upper free edge and also having a weighted end for normally causing it to assume a vertical position, whereby the guides when brought to horizontal positions by contact

with an obstruction will pass over without 55 engaging the ribs or projections of said obstruction.

2. The combination, with a carrier, of a contact-wheel, and a pair of disconnected guides loosely mounted upon the axis of said 60 wheel, each of said guides having an outwardly-flaring end and a recess or concavity adjacent to its upper free edge, whereby the guides when brought to horizontal positions 65 by contact with a switch or crossing-plate will pass over without engaging the guiding-ribs of said plate.

3. The combination, with a carrier, of a contact-wheel; a bolt upon which said wheel is mounted; and a pair of guides independently mounted for free swinging movement on said bolt adjacent to the sides of the wheel, each of said guides having an outwardly-flaring portion at one end, a recess adjacent to its upper free edge, and a weight at the other 75 end.

4. The combination, with a carrier, of a contact-wheel; a bolt upon which said wheel is mounted for rotation; a guide loosely mounted upon said bolt at one side of said 80 wheel, said guide having an outwardly-flaring end, a recess adjacent to its upper free edge, a shoulder projecting over the flange of the wheel, and a weighted extremity; and a second guide located upon said bolt on the 85 other side of said wheel and of the same construction as the first-named guide.

5. The combination, with a carrier, of a contact-wheel, and a pair of arms journaled for free swinging movement adjacent to the 90 sides of said wheel, each of said arms having guiding ends with concave sides, which, when the guides are horizontal, will pass over without engaging ribs or projections on a switch or crossing-plate.

6. The combination, with a carrier, of a contact-wheel supported for rotation thereon, and a pair of guiding arms or levers mounted for free swinging movement upon the carrier at each side of said wheel, each of said arms 100 or levers having a flaring forward end recessed or concaved on its outer side adjacent to its upper free edge and a weighted lower end.

ANTHONY J. GRIFFIN.
